CLAIM

The ornamental design for a wireless charger, as shown and described.

DESCRIPTION

FIG. 1 is a front, right and top perspective view of a wireless charger, showing our new design;

FIG. 2 is a rear, left, and bottom perspective view thereof;

FIG. 3 is a perspective view of the wireless charger shown in a state of use;

FIG. 4 is a front view of the wireless charger;

FIG. 5 is a rear view thereof;

FIG. 6 is a left side view thereof;

FIG. 7 is a right side view thereof;

FIG. 8 is a top plan view thereof;

FIG. 9 is a bottom plan view thereof;

FIG. 10 is an enlarged view of portion 10 of the wireless charger in FIG. 1;

FIG. 11 is an enlarged view of portion 11 of the wireless charger in FIG. 2;

FIG. 12 is an enlarged view of portion 12 of the wireless charger in FIG. 3;

FIG. 13 is an enlarged view of portion 13 of the wireless charger in FIG. 4;

FIG. 14 is an enlarged view of portion 14 of the wireless charger in FIG. 8; and,

FIG. 15 is an enlarged view of portion 15 of the wireless charger in FIG. 9.

The broken lines shown in the drawings illustrate portions of the wireless charger that form no part of the claimed design. The dot-dash broken lines depict the boundaries of the enlargements that form no part of the claimed design.

1 Claim, 15 Drawing Sheets
